Specification for Design.

Patented Dec. 28, 1920.

Application filed August 5, 1920. Serial No. 401,521. Term of patent 7 years.

To all whom it may concern:

Be it known that we, GEORGE V. STRAHAN and FREDERICK W. MATHIEU, citizens of the United States of America, and residents, respectively, of the city of Newark, county of Essex, and State of New Jersey, and of the borough of Manhattan, city, county, and State of New York, have invented a new, original, and ornamental Design for a Wall-Bracket for a Lighting-Fixture, of which the following is a specification, reference

being had to the accompanying drawings, forming part thereof.

Figure 1 is a perspective view and Fig. 2 is a top plan view, partly in section, of a wall bracket for a lighting fixture, showing our new design.

We claim:

The ornamental design for a wall bracket for a lighting fixture, as shown.

GEORGE V. STRAHAN.
